UNITED STATES PATENT OFFICE.

VINCENT PRICE, OF NEW YORK, N. Y., ASSIGNOR TO CHRISTINA J. HIGLEY, OF NEW YORK, N. Y.

SAFETY-PIN.

1,170,186.

Specification of Letters Patent.

Patented Feb. 1, 1916.

Application filed November 10, 1915. Serial No. 60,663.

To all whom it may concern:

Be it known that I, VINCENT PRICE, a citizen of the United States of America, residing at New York city, New York, have 5 invented a new and useful Safety-Pin, of which the following is a specification.

My invention relates to an improved safety pin, the object being to provide means to prevent the pin proper from bending 10 under strain to such a degree as to withdraw the point of the pin from the holding shield or to so buckle the pin as to break the same.

In the accompanying drawings: Figure 1 15 is a front elevation of my safety pin as it would appear in operation on a garment. Fig. 2 is a rear elevation thereof. Fig. 3 is a detailed view of the pin itself with the pin proper being open.

20 1 represents the pin portion of a safety pin of otherwise conventional form and which may include the usual coil 2, a suitable frame or back 3 and the pin receiving shield 4. In the particular form shown 25 herein which is illustrative of a preferable construction, the pin proper is provided with two downward bends 5 and 6 which form a substantial depression in the middle portion of the pin so that when the pin is pushed through a fabric and strain is applied, the fabric will be supported approximately at the points 7 and 8, that is to say, the strain will come close to the coil 2 and close to the shield 4 rather than in the middle 30 of the pin. By so constructing the pin that the strain occurs near the ends rather than in the middle the pin is much less liable

to bend and hence the danger of withdrawing the pin point from the shield 4 is practically eliminated. In the ordinary safety 40 pin construction in which the pin proper is straight, the fabric tends to gather and be drawn into the middle portion of the pin, so that when under strain the pin readily bends with disastrous results. By my improvement this tendency of the fabric to seek the middle of the pin is prevented by the resistance offered by the shoulders formed by the bends 5 and 6. These resistance shoulders may be provided in any de- 45 sired way and may be of course modified in degree although I have found that by fol- 50 lowing substantially the design and con- 55 struction illustrated herein, satisfactory re- sults may be achieved. The particular con- 60 struction is furthermore preferable because the resistance shoulders are formed inte- 65 grally with the pin thus saving the expense that would attend the providing of such shoulders by added means.

What I claim and desire to secure by Letters Patent is:

In a safety pin, a back, a shield at one end thereof, a yielding pin portion supported at the other end thereof, the point of the pin portion being arranged to be engaged by the shield, the intermediate part of the pin portion being bent toward the back to form opposite spaced resisting shoulders relatively near to the ends of the pin por- 70 tion to prevent the gathering of a fabric through which the pin is passed at the middle of the pin.

VINCENT PRICE.
